DUCKBILL SLEWING APPARATUS

Wilbur F. Frye, West Lafayette, Ohio

Application January 16, 1951, Serial No. 206,270

6 Claims. (Cl. 198—220)

1

This invention relates to mining equipment, and in particular loading devices of the type having a shovel with outwardly diverging sides carried by the leading end of a reciprocating trough or conveyor and this invention relates to means for throwing or slewing the scoop or duckbill from side to side as it is reciprocated.

The purpose of this invention is to provide a duckbill slewing device that is actuated by the reciprocating action of the duckbill and trough upon which the duckbill is carried.

Various types of instrumentalities have been used for slewing duckbills or laterally actuating scoops of reciprocating troughs or feeders for conveyors but devices of this type are actuated by independent motors and the combination of the reciprocating and lateral movements of the duckbill or scoop requires comparatively complicated and heavy operating mechanism and the upkeep and repair required by devices of this type in mines provides a serious problem. With this thought in mind this invention contemplates a method of training a cable in the supporting and operating instrumentalities of a duckbill whereby the duckbill is actuated laterally as it is reciprocated and the lateral action is accomplished by the method in which the cable is trained through the apparatus.

The object of this invention is, therefore, to provide means for slewing a duckbill that is operated by a reciprocating action of the duckbill and trough upon which it is carried.

Another object of the invention is to provide a method for training a cable through duckbill operating equipment for slewing the duckbill laterally as it is reciprocated that may readily be incorporated in equipment now in use.

A further object of the invention is to provide apparatus for actuating a duckbill laterally as it is reciprocated which is of a simple and economical construction.

With these and other objects and advantages in view the invention embodies a reciprocating trough having a duckbill or scoop carried by one end suspended above another trough and a cable, the ends of which are anchored at points spaced from the sides of the trough, and wherein the cable is trained over pulleys on stationary and movable parts of the apparatus whereby with the cable held at one side of the trough the duckbill is slewed by the cable as the duckbill and carriage are reciprocated longitudinally.

Other features and advantages of the invention will appear from the following description taken in connection with the drawings wherein:

2

Figure 1 is a plan view of the duckbill mounting equipment showing a cable trained through the equipment and with the ends thereof positioned at points spaced from the sides of the equipment.

Figure 2 is a side elevational view of the duckbill and mounting equipment as shown in Figure 1.

Figure 3 is a cross section through the apparatus showing the duckbill carrying trough suspended above the stationary trough and with pulleys journaled on a plate carried by the stationary trough.

Figure 4 is a detail illustrating one of the clamps for securing the cable to sides of the trough.

Figure 5 is an end elevational view of the clamp with the part of a trough to which the clamp is attached shown in section.

Figure 6 is a plan view similar to that shown in Figure 1 illustrating a modification wherein the clamps are replaced by friction brakes which alternately grip the cable.

Figure 7 is a cross section through the apparatus, taken on line 7—7 of Figure 6, also showing the reciprocating duckbill carrying trough and the stationary trough.

Figure 8 is a detail showing a side elevational view of one of the brakes or friction gripping elements, with parts broken away.

Figure 9 is a detail showing a plan view of the friction block forming brake shown in Figures 6 and 8.

Figure 10 is a detail showing a section through the friction blocks of the brake.

Figure 11 is a cross section taken on line 11—11 of Figure 10 showing the friction blocks of the brake.

Figure 12 is a detail similar to that shown in Figure 8 showing a side elevational view of a drum which provides a further modification in that the drum replaces the friction brake or clamp.

Figure 13 is a plan view of the drum mounting illustrated in Figure 12.

Figure 14 is a detail showing an end elevational view of the drum shown in Figure 12.

Referring now to the drawings wherein like reference characters denote corresponding parts the duckbill slewing apparatus of this invention includes a cable 10, a duckbill 11 carried by a shovel trough 12, a feeder trough 13, a transversely disposed plate 14 attached to the feeder trough 13 and a shoe 15 carried by the reciprocating or shovel trough 12.

With the parts arranged as illustrated in Figure 1 one end 16 of the cable 10 is anchored to a post 17 and the opposite end 18 is anchored to a post 19. The cable extends from the post 17 around a sheave 20 on the plate 14, to the sheave 21 on the shoe 15, from the sheave 21 to a sheave 22 on the forward end of the shovel trough, from the sheave 22 to a sheave 23 on the forward end of the plate 14, from the sheave 23 around the sheave 24, on the shovel trough 12, from the sheave 24 to the sheave 25 on the shoe 15, from sheave 25 around the sheave 26 on the plate 14, and extends from the sheave 26 to the anchor post 19.

The shovel trough 12 is provided with pivotal operating devices 27 and 28, of the conventional type by which the trough, on the forward end of which the duckbill or shovel is positioned is reciprocated, and as the trough is reciprocated with the cable free it will travel on a straight line extended through the longitudinal center of the apparatus.

When it is desired to swing the shovel or duckbill laterally one of the clamping devices 29 or 30, carried by the plate 14 and through which the cable extends is actuated to grip the cable, and when it is desired to swing the duckbill to the right the clamp 29 on the right hand side of the trough is actuated to grip the cable whereby with the cable held at that point the duckbill will swing to the right as the trough is reciprocated. By the same means the duckbill is reciprocated to the left by actuating the clamp 30 at the left hand side of the trough.

As illustrated in Figures 4 and 5 the clamps 29 and 30 are formed with downwardly extended plates and corresponding plates, as indicated by the numeral 31 are urged toward the clamping plates by thumb nuts 32 on screws 33 which are carried by the clamp plates 29 and 30 and extend through openings in the plates 31. The cable 10 is positioned between the plates 29 and 31 and the plates are secured to the plates 14, by welding, as shown in Figure 5, or by other suitable means.

In the design illustrated in Figure 6 a cable 40, similar to the cable 10 is anchored to posts 41 and 42 and the cable extends from the post 41 around a sheave 43 on a plate 44, similar to the plate 14, from the sheave 43 around a sheave 45 on a sliding shoe 46, from the sheave 45 to a sheave 47 in the shovel trough, from the sheave 47 around a sheave 48 on the plate 44, and from the sheave 48 around a sheave 49 also on the shovel trough, from the sheave 49 around a sheave 50 on the opposite side of the shoe 46 and from the sheave 50 around a sleeve 51 on the plate 44 to the anchor post 42.

Between the sheaves 45 and 47 on one side and 49 and 50 on the opposite side the cable extends through friction brakes 52 and 53, shown in detail in Figures 8, 9 and 10 wherein tapering sleeves 54 and 55 are mounted in an opening 56 in a block 57. The sleeves 54 and 55 are provided with sections 58 and 59 of a collar and a ring 60 is positioned in semi-circular grooves 61 and 62 of the collar whereby with the ring actuated by a hand lever 63 through arms 64 and 65 the sections are actuated outwardly from the block 57 to release the cable and inwardly to clamp the cable so that clamping means similar to the blocks 29 and 30, shown in Figure 1, are provided on opposite sides of the device.

The levers 64 and 65 are provided with yokes 66 that extend over pins 67 and 68, respectively which extend from opposite sides of the ring 60.

The hand lever 63, and the arms 64 and 65 are mounted on a shaft 69, which is journaled in bearings 70 and 71 of a frame 72, and the shaft is provided with a lever 73 that actuates a similar brake mechanism on the opposite side of the trough with the extended end of the lever 73 connected by a yoke 74 and a bolt 75 to an arm 76 on a cross shaft 77. A similar arm is provided on the opposite end of the shaft 77, as indicated by the numeral 78 and this arm is connected to a shaft 79, similar to the shaft 69 through a lever 80, a yoke 81 and the bolts 82, similar to corresponding parts of the brake device on the opposite side of the trough. The shaft 77 is journaled in bearings 83 and 84 extended from the plate 44 which is attached to the under side from the feeder trough 85, similar to the trough 13.

The brakes 52 and 53 are mounted on brackets 86 and 87 and springs 88 are provided between the ends of the tapering members 54 and 55 and an upwardly extended end 89 of the bracket.

In the design illustrated in Figures 12, 13 and 14 the friction blocks or brake devices are replaced by drums 90 around which a cable 91 is wrapped and the drums are mounted on shafts 92, the lower ends of which are journaled in plates 93, similar to the plates 14 and 44, and the upper ends of which are journaled in brackets 94. The upper ends of the drums 90 are provided with brake drums 95 and brake bands 96 are positioned around the drums. The ends 97 and 98 of the brake bands extend outwardly, as shown in Figure 13 and cams 99 and 100, positioned on a shaft 101, and actuated by a hand lever 102 urge the ends together when it is desired to grip and hold the cable drums stationary. Springs 103 are provided between the ends 97 and 98 urging the ends outwardly to release the brake drums when the ends are released by the cams. The shaft 101 is journaled in the bracket 104 and the hand lever 102 urged upwardly by a spring 105.

The springs 105 are mounted in upwardly extended plates 106 and cable guides 107 extend from the plate 106 to the plate 93 as shown in Figure 14. Idler pulleys 108 are provided on brackets 109 at the opposite sides of the drums and sheaves 110, similar to the sheaves 43 and 51 are journaled on the under side of the plate 93.

The duckbill slewing apparatus may, therefore, be provided with means for clamping or directly gripping the cable on either side of the trough or the cable may be wrapped around drums and the braking elements provided on the drums.

With the parts arranged in this manner the gripping device on the right hand side of the trough is tightened when it is desired to swing the shovel to the right, and as the cable is locked on the right hand side, that part thereof between the right hand sheave 43 and the anchor 41 will be decreased in length causing the duckbill to be pulled to the right as the shovel trough is reciprocated. By the same means the gripping device on the left hand side of the trough may be tightened and the gripping device on the right hand side released when it is desired to swing the duckbill or shovel to the left. With both of the gripping devices released the shovel trough will reciprocate in a straight line on the longitudinal center of the feeder trough.

In operation the sliding shoe 15, which is movable with the shovel trough 12, carries a pair of sheaves 21-25, one on each side. At the forward end, the shovel trough carries a pair of sheaves 22-24, one on each side. A plate

14, is carried by the feeder trough and it, in turn, carries a pair of sheaves 20-26, one on each side. In addition, the plate carries a forwardly disposed centrally located sheave 23. The plate 14 also carries a pair of identical rope gripping devices 29-30, which are engageable with the inner strands of rope 10. The rope is arranged as shown, being connected to the sockets 17-19 which are anchored at opposite sides of the duckbill.

When the duckbill is loading, but is not swinging, both gripping devices 29 and 30 will be loose. To swing to the right, the right hand gripping device 29 is tightened, following which the operator retracts the shovel trough in the usual manner, thereby causing the distance between the sheaves 21-25 and 20-26 to increase. Since the rope is locked in gripping device 29, that part between the right hand sheave 20 and socket 17 will be decreased in length, causing the duckbill to be pulled to the right. Conversely, if only the gripping device 30 is tightened, the duckbill will be swung to the left when the shovel trough is retracted.

On the other hand, if the shovel trough is extended while gripping device 29 is tight, the duckbill will be swung to the left. Similarly, if the shovel trough is extended while gripping device 30 is tight, the duckbill will be swung to the right.

The power to swing the duckbill from right to left is taken from the shovel trough rails by gripping of the grip blocks controlled by the operating levers of the operating carriers, the operating carriers being driven by the feeder trough, and the feeder trough being driven by the pan line.

It will be understood that other modifications may be made in the design and arrangement of the parts without departing from the spirit of the invention.

What is claimed is:

1. A duckbill slewing device comprising a feeder trough, a shovel trough having a shovel on the forward end suspended above and aligned with the said feeder trough, a shoe carried by the trailing end of the shovel trough, a plate positioned adjacent the shovel end of the feeder trough and mounted on the under surface thereof, sheaves journaled on the shoe, plate, and shovel, a cable extended around the sheaves on the shoe, shovel and plate and extended laterally from the sides of the trough, means anchoring the ends of the cable at points spaced from the sides of the troughs, and cable gripping means mounted on the plate and positioned on opposite sides of the troughs.

2. A duckbill slewing device comprising a feeder trough, a shovel trough having a shovel on the forward end suspended above and aligned with the said feeder trough, a shoe carried by the trailing end of the shovel trough, a plate positioned adjacent the shovel end of the feeder trough and mounted on the under surface thereof, sheaves on the ends of the plate and positioned on opposite sides of the said trough, a centrally positioned sheave journaled on the said plate and positioned midway of the ends thereof, sheaves on the ends of the shoe and also positioned on opposite sides of the trough, sheaves journaled on opposite sides of the shovel, a cable extended around the sheaves on the ends of the plate positioned intermediate of the ends of the trough, around sheaves on the ends of the shoe carried by the shovel trough, around

sheaves on the shovel, around the centrally positioned sheave on the plate, and extended from the sheaves on the ends of the plate to anchoring points spaced from the sides of the trough, and cable gripping elements carried by the said plate and positioned on opposite sides of the trough.

3. A duckbill slewing device comprising a feeder trough, a shovel trough having a shovel on the forward end suspended above and aligned with the said feeder trough, a shoe carried by the trailing end of the shovel trough, a plate positioned adjacent the shovel end of the feeder trough and mounted on the under surface thereof, sheaves on the ends of the plate and positioned on opposite sides of the said trough, a centrally positioned sheave journaled on the said plate and positioned midway of the ends thereof, sheaves on the ends of the shoe and also positioned on opposite sides of the trough, sheaves journaled on opposite sides of the shovel, a cable trained over a sheave on one end of the said plate, over a sheave on the shoe, around a sheave on the shovel, around the sheave on the center of the plate, around a sheave on the opposite side of the shovel, around a sheave on the opposite end of the shoe, and around a sheave on the opposite end of the said plate, means anchoring the ends of the cable at points spaced from the sides of the trough, and gripping means on both sides of the trough for alternately gripping the cable.

4. A duckbill slewing device comprising a feeder trough, a shovel trough having a shovel on the forward end suspended above and aligned with the said feeder trough, a shoe carried by the trailing end of the shovel trough, a plate positioned adjacent the shovel end of the feeder trough and mounted on the under surface thereof, sheaves on the ends of the plate and positioned on opposite sides of the said trough, a centrally positioned sheave journaled on the said plate and positioned midway of the ends thereof, sheaves on the ends of the shoe and also positioned on opposite sides of the trough, sheaves journaled on opposite sides of the shovel, a cable extended around the sheaves on the ends of the plate positioned intermediate of the ends of the trough, around sheaves on the ends of the shoe carried by the shovel trough, around sheaves on the shovel, around the centrally positioned sheave on the plate, and extended from the sheaves on the ends of the plate to anchoring points spaced from the sides of the trough, and thumb screw actuated clamps mounted on the ends of the said plate and positioned on opposite sides of the trough for alternately clamping the cable to the plate.

5. A duckbill slewing device comprising a feeder trough, a shovel trough having a shovel on the forward end suspended above and aligned with the said feeder trough, a shoe carried by the trailing end of the shovel trough, a plate positioned adjacent the shovel end of the feeder trough and mounted on the under surface thereof, sheaves on the ends of the plate and positioned on opposite sides of the said trough, a centrally positioned sheave journaled on the said plate and positioned midway of the ends thereof, sheaves on the ends of the shoe and also positioned on opposite sides of the trough, sheaves journaled on opposite sides of the shovel, a cable extended around the sheaves on the ends of the plate positioned intermediate of the ends of the trough, around sheaves on the ends of the shoe carried by the shovel trough, around sheaves

on the shovel, around the centrally positioned sheave on the plate, and extended from the sheaves on the ends of the plate to anchoring points spaced from the sides of the trough, and lever actuated friction gripping blocks mounted on the said plate and positioned to receive the cable on opposite sides of the troughs for alternately gripping the cable at the sides of the troughs.

6. A duckbill slewing device comprising a 10
feeder trough, a shovel trough having a shovel
on the forward end suspended above and aligned
with the said feeder trough, a shoe carried by
the trailing end of the shovel trough, a plate pos-
15
itioned adjacent the shovel end of the feeder
trough and mounted on the under surface there-
of, sheaves on the ends of the plate and pos-
itioned on opposite sides of the said trough, a
centrally positioned sheave journaled on the said
plate and positioned midway of the ends there-
20
of, sheaves on the ends of the shoe and also
positioned on opposite sides of the trough,
sheaves journaled on opposite sides of the shovel,

5
15
20

a cable trained over a sheave on one end of the
said plate, over a sheave on the shoe, around a
sheave on the shovel, around the sheave on the
center of the plate, around a sheave on the op-
posite side of the shovel, around a sheave on
the opposite end of the shoe, and around a
sheave on the opposite end of the said plate,
means anchoring the ends of the cable at points
spaced from the sides of the trough, drums jour-
naled on the said plate and positioned on op-
posite sides of the troughs, the said cable being
wrapped around the said drums, and brakes for
temporarily holding the said drums.
